UNITED STATES PATENT OFFICE.

JOHN BINGEN AND WILLIAM A. BEAVER, OF MARSHFIELD, WISCONSIN.

COW-TAIL HOLDER.

1,255,284.

Specification of Letters Patent.

Patented Feb. 5, 1918.

Application filed July 13, 1917. Serial No. 180,355.

To all whom it may concern:

Be it known that we, JOHN BINGEN and WILLIAM A. BEAVER, citizens of the United States, residing at Marshfield, in the county 5 of Wood and State of Wisconsin, have invented certain new and useful Improvements in Cow-Tail Holders, of which the following is a specification, reference being had therein to the accompanying drawing.

10 This invention relates to an improved device for holding a cow's tail while the cow is being milked.

The object of the invention is to provide a device, of this character, constructed from 15 a single piece of sheet spring material, having a tail engaging loop and a leg engaging portion comprising elongated rolls.

A further object is to provide a spring clamp having projection and aperture means 20 in the tail engaging loop section, for preventing the slipping of the holder on the cow's tail.

A further object is to provide the leg engaging ends of the clamping arms with apertures, into which the flesh is forced by the 25 clamping action, thereby preventing slipping of the clamp on the leg of the cow.

A further object is to provide the tail engaging loop with spring tongues, so that 30 after the holder has been placed on the tail, it can be further prevented from slipping, by passing the hair on the cow's tail upwardly and downwardly and clamping the same under said spring tongues.

35 With the above and other objects in view, which will appear as the description proceeds, the invention resides in the details of construction and combination and arrangement of parts, hereinafter described and 40 claimed, it being understood that changes in the precise embodiment of the invention herein described can be made within the scope of what is claimed, without departing from the spirit of the invention.

45 In the drawing:—

Figure 1 is a perspective view of the device.

Fig. 2 is a view showing the device applied to a cow's tail and leg.

50 Fig. 3 is a sectional view on line 3—3 of Fig. 1.

Fig. 4 is a perspective view of another form of the invention, showing apertures in the tail engaging loop and also in the leg 55 engaging arms and rolls.

Fig. 5 is a view showing the apertured form applied to a cow's tail and leg.

Fig. 6 is a perspective view of another form of the invention, showing spring tongues carried by the tail engaging loop. 60

Fig. 7 is a top plan view of the same, showing the tongues clamping the hair of a cow's tail.

Fig. 8 is a section on line 8—8 of Fig. 6, showing the hair clamped under the tongues. 65

Referring to the drawings, 1 designates one of the hind legs of a cow, 2 the hock thereof and 3 the tendon leading from said hock. The holder 5 is formed from a single piece of sheet spring metal, curvally bent 70 upon itself as at 6, thereby forming a loop and also forming arms 7 and 8, each arm is provided with compound curves 9 and 10, the extreme ends of the arms 7 and 8 are formed into rolls 11. The rolls 11 are adapted 75 to engage the flesh of the leg of a cow so that the rolls 11, will engage the leg in such a manner so that the skin and fleshy part of the leg, including the tendon 3, will be received by the opening 12, formed by the 80 arms of the holder. The tail engaging loop 13, is provided with struck in spurs 14, adapted to engage the cow's tail when the holder is sprung around the same. It will be seen that a holder is provided in which 85 positive holding of the cow's tail during the milking operation is assured.

In Figs. 4 and 5 another form of the invention is shown, there being apertures 15 in the tail engaging looped portion of the 90 holder and also apertures 16 and 17 in the rolls 11 and arms 7 and 8. These apertures 15, 16 and 17 are adapted to receive the skin and flesh of the cow's tail and leg when the holder is clamped thereon, as shown at 18, 95 thereby providing means for preventing slipping of the holder on the tail or leg of the cow.

In Figs. 6, 7 and 8 another form of the invention is shown. This form is provided 100 with tongues 19, which are adapted to receive the hair on the tail of the cow and securely clamp the same into the elongated apertures 20. The best method of doing the same is for some of the hair to be passed 105 upwardly from below the tail engaging loop and some downwardly from above the tail engaging loop, in both cases the hair is clamped under the tongues which being made of spring material will clamp the hair 110

into and in engagement with the elongated slots.

The invention having been set forth what is claimed as new and useful is:

- 5 1. A device of the class described comprising a single piece of spring metal bent to form a tail engaging loop having spring tongues integral with said loop and normally within elongated slots at diametrically opposite points of said loop and being adapted to receive hair on the tail of the cow thereby additionally preventing slipping of the holder, arms extending rearwardly and curving outwardly and inwardly thereby forming a recess for the reception of the flesh and the converging ends of said arms having rolls to engage and press upon and clamp the flesh of the leg of a cow.
- 10 15 2. A device of the class described comprising a piece of spring metal bent to form a tail engaging loop having spring tongues in-

tegral therewith and normally within elongated slots at diametrically opposite sides 20 of said loop and having outwardly bent ends adapted to be engaged by the finger for releasing the hair, said tongues being adapted to receive the hair on the tail of a cow thereby additionally preventing slipping of the 25 holder, arms extending rearwardly and curving outwardly and inwardly thereby forming a recess for the reception of the flesh and the converging ends of said arms having rolls to engage and press upon and 30 clamp the flesh of the leg of a cow.

In testimony whereof we hereunto affix our signatures.

JOHN BINGEN.

WILLIAM A. BEAVER.
